UNITED STATES PATENT OFFICE.

GUSTAVE E. VILLARET, OF LEONIA, NEW JERSEY, ASSIGNOR TO THE AMERICAN PIN COMPANY, DIVISION SCOVILL MANUFACTURING COMPANY, OF WATERBURY, CONNECTICUT, A CORPORATION OF CONNECTICUT.

DESIGN FOR A SHIELD FOR USE AS A PART OF A LIGHTING FIXTURE.

Application filed February 19, 1926. Serial No. 16,591. Term of patent 3½ years.

To all whom it may concern:

Be it known that I, GUSTAVE E. VILLARET, a citizen of the United States, residing at Leonia, county of Bergen, and State of New Jersey, have invented a new, original, and ornamental Design for a Shield for Use as a Part of a Lighting Fixture, of which the following is a specification, reference being had to the accompanying drawing, forming part thereof.

In the drawing Figure 1 is a front elevation, and

Fig. 2 a side view showing a shield for use as a part of a lighting fixture in accordance with my new design.

I claim:

The ornamental design for a shield for use as a part of a lighting fixture, as shown.

GUSTAVE E. VILLARET.
